UNITED STATES PATENT OFFICE.

WILLARD C. FISK, OF SEATTLE, WASHINGTON, ASSIGNOR TO CHARLES E. BORTON AND EDWARD L. PERKINS, BOTH OF KING COUNTY, WASHINGTON.

DESIGN FOR A CLASP FOR WATCH-FOBS.

• 50,343.

Specification for Design.

Patented Feb. 20, 1917.

Application filed November 13, 1916. Serial No. 131,151. Term of patent 3½ years.

To all whom it may concern:

Be it known that I, WILLARD C. FISK, a citizen of the United States, and a resident of Seattle, in the county of King and State of Washington, have invented a new, original, and ornamental Design for a Clasp for Watch-Fobs, of which the following is a specification, reference being had to accompanying drawing, forming a part thereof.

In the drawings Figure 1 is a front elevation of a clasp for watch fobs illustrating my new design. Fig. 2 is a side elevation of same.

I claim:

The design for a clasp for watch fobs as shown.

WILLARD C. FISK.
